CAMP STOVE

Wilford W. Wilkinson, Cleveland, Ohio

Application June 28, 1932. Serial No. 619,797

8 Claims. (Cl. 126—9)

My invention relates to camp stoves and more particularly to a knockdown utility device for hunters, campers, travelers and others; and the object is to provide a simple device adapted for 5 a variety of uses, to provide a device which can be quickly assembled and quickly knocked down, and quickly packed in a small package or assembled ready for use, and to provide a device which can be furnished at small cost. Other objects and advantages will be fully explained in 10 the following description and the invention will be more particularly pointed out in the claims.

In the accompanying drawing like characters of reference indicate like parts in the several 15 views, and:

Figure 1 is a perspective view of the stove assembled.

Figure 2 is a perspective view of the device knocked down and packed.

20 Figure 3 is an enlarged plan view of the stove assembled.

Figure 4 is an end view of the device, as shown in Figure 3, partly in section.

25 Figure 5 is an enlarged detail section on the line 5—5 of Figure 3.

Figure 6 is a section similar to Figure 5 but showing a modification of the side holding means.

In the embodiment of the invention as here disclosed there is provided a fire box bottom 10 30 having upturned flanges 11 at its edge. The bottom 10 is provided with a series of slots 13 so that this bottom forms a species of grate. Also, adjacent each corner of the bottom there is provided a leg hole or socket 14. Legs 15 are 35 provided to support the bottom and each leg has a reduced upper end 16 which projects upwardly through a respective hole or socket 14 and extends upwardly adjacent the flanges 11, each leg being shouldered at the junction of the 40 body and extension so that the bottom rests on the leg shoulders. The bottom thus forms a shallow tray which, when the stove is packed for transportation, forms the lower part of a shallow box. An ash pan 17 is provided on 45 which the legs rest when the stove is set up and this pan has inwardly inclined side edges 18 which, when the stove is packed, engage over ribs 19 formed on the outside of certain parts of the flanges 11.

50 Side walls 20 of sheet metal are provided and the lower corners of these side walls fit between the flanges 11 and extensions 16. The upper edges of opposite side walls, as shown in Figures 1 to 5, are connected by bars 21 which have down turned ends 22 engaging against the outer faces

of the side walls. These bars 21 are also provided, adjacent the ends 22, with notches 23 which receive portions of the edges of the side walls as best seen in Figure 5. By this means the side walls are supported in vertical position on 60 the bottom and are prevented from moving both inwardly and outwardly at their upper edges. Furthermore, the bars 21 form a grill on which the cooking utensils may be supported and, for broiling or toasting, the food itself may even be 65 supported on this grill.

In the form shown in Figure 6 the side walls 20 are provided with beads 24 at their upper edges and the bars 21 are replaced by bars 25 which carry at their ends downwardly opening C-shaped 70 clips engaging the beads as shown, the metal of the bars being bent upwardly, outwardly and downwardly at each end to C form.

In packing the device for transportation or storage the bars are removed from the fire box 75 walls and these are then lifted off the slotted bottom. The legs are now removed from the bottom and placed therein with the sides and bars. Finally the ash pan is turned upside down and 80 slid onto the bottom with its flanges engaging the ribs on the side flanges of the bottom. The ash pan thus forms a cover for the shallow tray-like bottom and all the parts are securely held together.

Obviously, the device may be used for cooking, 85 as a stove for heating a tent and for heating water as well as for other purposes to which stoves are usually applied.

There has thus been provided a simple and 90 efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is 100 claimed as new, is:

1. In a collapsible stove, a bottom having slots 105 therein and provided with leg receiving openings at its corners, flanges extending upwardly from the periphery of said bottom, legs having reduced ends and supporting said bottom, said reduced ends being removably engaged in the leg receiving openings and extending upwardly alongside of and slightly spaced from said flanges, and side walls removably fitted between said legs and 110 flanges and positioned thereby.

WILFORD W. WILKINSON
